United States Patent Office.

ISAAC STARR, JR., OF PHILADELPHIA, PENNSYLVANIA.

Design No. 3,677, dated September 28, 1869.

DESIGN FOR A CARPET-PATTERN.

The Schedule referred to in these Letters Patent and making part of the same.

To all whom it may concern:

Be it known that I, ISAAC STARR, Jr., of Philadelphia, county of Philadelphia, State of Pennsylvania, have originated a new Design for a Carpet-Pattern; and I do hereby declare that the accompanying drawing, and following explanation thereof, form a full, clear, and exact description of the said design.

In the drawing is represented sufficient of a carpet to show my design, the central figure of which consists of a leaf, *a*, there being on each side of this leaf a square figure, *B*, of the character clearly shown in the drawing, and opposite each end of the leaf, another square, *C*, of a design entirely different from the squares *B*.

Surrounding each of the figures *C* is a row of diamond-shaped spots, *f*, and at right angles to this row of spots, and extending to each end of the leaf *a*, is a

wide bar, *h*, composed of zigzag lines and rows of diamonds.

Each of the figures *B* is surrounded by foliated ornaments, *i*, the character of which is too clearly shown in the drawing to need description.

Irrespective of the colors employed,

I claim the design for a carpet-pattern, substantially as described, and as represented in and by the accompanying drawing.

In testimony whereof, I have signed my name to this specification, in the presence of two subscribing witnesses.

ISAAC STARR, JR.
